F. H. BROWN

REGULATING MECHANISM

Filed May 22, 1920

UNITED STATES PATENT OFFICE.

FRANCIS H. BROWN, OF GLEN OLDEN, PENNSYLVANIA, ASSIGNOR TO PETROLEUM HEAT AND POWER COMPANY, OF BOSTON, MASSACHUSETTS, A CORPORATION OF DELAWARE.

REGULATING MECHANISM.

Application filed May 22, 1920. Serial No. 383,553.

To all whom it may concern:

Be it known that I, FRANCIS H. Brown, a citizen of the United States, residing at Glen Olden, in the county of Delaware and State of Pennsylvania, have invented an Improvement in Regulating Mechanism, of which the following description, in connection with the accompanying drawings, is a specification, like characters on the drawings representing like parts.

The invention to be hereinafter described relates to regulating mechanism adapted to be used in connection with furnaces of steam generators and for other purposes.

In regulation of combustion conditions it is desirable that the apparatus shall be responsive to a plurality of factors, such, for example, as variations in the pressure of the steam developed by the generator, and variations in the pressure of the kinetic steam or the steam flowing from the generator in accordance with the load or demand thereon. It is desirable that the apparatus shall be sensitive to slight variations in the pressure, and that these variations may be employed to regulate the supply of fuel, the draft or other conditions attending combustion, but that the apparatus shall have sufficient power positively to control the means regulated thereby.

One of the purposes of the present invention, therefore, is to provide a mechanism which will be responsive to a plurality of conditions or factors, such, for example, as variations in static and kinetic pressure of the steam developed by a generator, and control the supply of motive fluid to a motor which will furnish sufficient power positively to operate the instrumentality to be controlled thereby.

In the present instance of the invention, the motor is in the form of a cylinder containing a piston and provided with a pilot valve for controlling the supply of compressed air or other motive fluid to the cylinder. It is desirable that the piston shall be moved in the cylinder with a varying length of travel depending upon the extent of control required. In other words, it is desirable that the piston shall be moved a certain amount and then automatically arrested, and the point of arrest should be varied from time to time.

Another purpose of the invention, there-

fore, is to provide simple and efficient means which may be operated by movement of the motor or piston automatically to arrest the same as required, and this arrest may occur after the pilot valve has been shifted by either of the devices responsive to variations in static and kinetic steam pressure.

With the aforesaid and other purposes in view, the character of the invention may be best understood by reference to the following description of one good form thereof shown in the accompanying drawing, wherein:

Fig. 1 is a front elevation of a regulating mechanism embodying the invention, certain parts thereof being shown in section; 70

Fig. 2 is a horizontal section taken on line 2-2 of Fig. 1;

Fig. 3 is a horizontal section taken on line 3-3 of Fig. 1; and

Fig. 4 on an enlarged scale is a perspective view of parts shown in Fig. 1.

Referring to the drawing, any suitable form of motor may be employed, in the present instance, comprising a cylinder 1 containing a piston 3 connected by a stem 5 with a frame 7 guided in extensions on the cylinder 1 and provided with upper and lower eyes 9 and 11 adapted to be connected to any regulating instrumentality to be controlled thereby, such, for example, as valve mechanism for controlling the feed of fuel to the furnace, and dampers for controlling the draft for the furnace.

13 designates the steam main of a steam generator which may be of any suitable form of well known construction, and therefore, it is unnecessary to show the same herein. An orifice device 15 may be mounted in this steam main, desirably of the construction disclosed in my copending application Serial No. 368,665, filed March 25, 1920.

As stated, the motor may be operated in response to varying conditions, but for purposes of exemplification, in the present instance, the motor is operated in response to variations in static and kinetic steam pressure.

The device responsive to static steam pressure, in the present instance, comprises a casing 17 containing a diaphragm 19, said casing being conveniently mounted directly beneath the cylinder 1. The upper side of

the diaphragm 19 may be subjected to variations in static pressure of the steam through a pipe 21 communicating with the static pressure side of the orifice device 15, said pipe being provided with a usual valve 23.

The device responsive to variations in kinetic pressure of the steam, in the present instance, comprises a casing 25 containing a diaphragm 27, the upper side of which may be subjected to variations in kinetic steam pressure through a pipe 29 communicating with the orifice of the device 15, said pipe being provided with a usual valve 31.

Kinetic pressure may be obtained within the pipe 29 by forming the orifice device 15 so that communication is provided between the end of the pipe 29 and the inner periphery of the orifice in the device 15, the arrangement being such that the pressure will be taken at the point where the steam passes through the orifice, since at this point the pressure varies in accordance with the flow of steam. And static pressure may be obtained within the pipe 21 by forming the orifice device 15 with ports leading from one or both sides of the orifice device to the end of the pipe 21 so that the pressure may be taken to one side of the path of travel of the steam through the orifice in the device 15, all as more fully set forth in the application above mentioned.

It is desirable that the opposite sides of the diaphragms 19 and 27 shall be subjected to a yielding pressure in opposition to the static and kinetic pressures on the upper sides thereof. To accomplish this, in the present instance, a cylinder 33 may be provided containing an inverted cup 35 and adapted to be filled with water or other liquid so as to leave an air cushion 37 in the cup. The casing may communicate with the under side of the diaphragm 19, and the under side of the diaphragm 27 respectively through branch pipes 39 and 41 connected in turn by a pipe 43 with the casing 33, said branch pipes being provided with valves 45 and 47.

It is desirable that the air cushion shall be subjected to a predetermined working pressure which may desirably be the working pressure of the steam desired in the main 13. To establish this pressure in the casing 33, a pipe 49 may be provided having one end communicating with the pipe 21 referred to, and its other end communicating with the casing 33, the pipe 49 being provided with a usual valve 51. The construction is such that when the valves 23 and 51 are opened, the casing 33 will be subjected to the static pressure of the steam in the main 13, and after this pressure has been established in said casing, the valve 51 may be closed so as to maintain the same therein, and the lower sides of the diaphragms 19

and 27 will be subjected to this pressure upon opening the valves 45 and 47.

If the pressures above the diaphragms 19 and 27 equal the predetermined working pressure established on the cushion, the diaphragms will remain stationary, but if the static and kinetic pressures above said diaphragms rise above or fall below such pressure, the diaphragms will be moved accordingly.

As stated, one of the purposes of the present invention is to provide a mechanism which will be responsive to a plurality of conditions, such, for example, as variations in static and kinetic steam pressure for controlling the pilot valve to control in turn the admission of motive fluid into the cylinder 1. This mechanism, in the present instance, is in the form of a system of levers comprising a main lever 53 fulcrumed on a bracket 55 conveniently mounted on the cylinder 1. One end of said lever is connected by an extensible link 57 with a yoke lever 59 pivotally connected to the diaphragm 19 and fulcrumed on the casing 17. The opposite end of the lever 53 has a bell-crank 61 pivotally mounted thereon, the arm 63 of said bell-crank being connected by a link 65 with the rod of the pilot valve 67 mounted on the cylinder 1 for controlling the supply of motive fluid to said cylinder from any suitable source. Since this pilot valve may be of well known construction, it is unnecessary to show and describe the same in detail herein.

The other arm 69 of the bell-crank may be pivotally connected by a link 70 to one end of a transmitting lever 71 fulcrumed intermediate its end on a rock arm 73 fulcrumed on a bracket 75 conveniently mounted on an extension of the lower head of the cylinder 1. The rock arm may have an arm 77 projecting substantially at right angles thereto connected by an extensible link 79 with a yoke lever 81 pivotally connected to the diaphragm 27 and fulcrumed on the casing 25.

The upper end of the transmitting lever 71 may be connected by a link or member 83 with the upper end of a rock arm or standard 85 having its lower end pivotally mounted on a bracket 87 conveniently mounted on an extension of the lower head of the cylinder 1.

Pivotaly mounted on the standard 85 is a shoe 89 having an inclined bar 91 slidably mounted therein, the lower part of said bar being pivotally connected to and carried by a bracket 92 on the reciprocating frame 7 referred to. This bar may be set at different angles of adjustment with respect to said frame by an adjusting screw 93.

In operation, variations in static steam pressure will be transmitted through the pipe 21 to the upper side of the diaphragm 19

19, thereby moving the latter. This movement will rock the yoke lever 59 and through the extensible link 57 will rock the main lever 53, thereby moving the bell-crank so as to shift the pilot valve to admit the motive fluid into the cylinder 1. This will cause movement of the piston 3 and the frame 7, and cause the inclined bar 91 to slide in the shoe 89, thereby 10 rocking the standard 85. This movement of the standard in turn will operate through the link 83 and the transmitting lever 71 to rock the bell-crank 61 so as to shift the pilot valve oppositely to its previous direction, 15 and thereby cut off the supply of motive fluid to the cylinder and arrest the piston 3.

Variations in the kinetic steam pressure of the steam will be transmitted through the pipe 29 to the upper side of the diaphragm 27, thereby causing movement of the latter, which will be transmitted through the yoke lever 81 to the extensible link 79. This will move the rock arm 73 and the transmitting lever 71 so as to rock the bell-crank and 25 shift the pilot valve to admit motive fluid to the cylinder 1. This will cause movement of the piston 3 and the frame 7, and cause the inclined bar 91 to slide in the shoe 89, thereby 30 rocking the standard 85. This movement of the standard in turn will be imparted through the link 83 and the transmitting lever 71 to rock the bell-crank so as to shift the pilot valve oppositely to its previous direction and cut off the supply of motive fluid 35 to the cylinder, thereby arresting the piston.

The connections between the pilot valve and the diaphragms are such that the pilot valve is at all times under the control of each diaphragm, and its position at any instant will depend upon the combined displacement of the two diaphragms at that instant, and the position of the bar 91.

The extent of movement of the piston 3 in the cylinder 1 will depend upon the angle of inclination of the inclined bar 91 with respect to the reciprocating frame 7. By means of the adjusting screw 93 the inclined bar may be set at any angle desired, so that the piston will have a greater or less travel 45 in the cylinder according to the amount of regulating movement of the frame 7 required.

Thus, by the simple system of levers described, the motor is operated from a plurality of independent devices or sources of power, and the motor is automatically arrested in response to the movement thereof.

While the invention has been described more particularly in connection with its use for regulating apparatus employed in connection with furnaces or steam generators, it will be understood that it may be applied to other purposes as desired.

It will be understood that the invention is not limited to the specific embodiment shown,

and that various deviations may be made therefrom without departing from the spirit and scope of the appended claims.

What is claimed is:—

1. The combination of a cylinder, a piston 70 therein, a stem for said piston, a frame connected to said stem, a pilot valve for controlling the supply of motive fluid to said cylinder, and means for operating said pilot valve comprising a main lever, a bell-crank 75 pivoted on said main lever and having an arm connected to said pilot valve, primary operating means connected to said main lever for moving said main lever and bell-crank to operate the pilot valve to admit 80 motive fluid to said cylinder, primary operating means connected to the other arm of the bell-crank for moving the latter to operate the pilot valve to admit motive fluid to said cylinder, and means operated by movement of said piston and frame for moving the bell-crank to operate the pilot valve to cut off the supply of motive fluid to said cylinder.

2. The combination of a cylinder, a piston 90 therein, a pilot valve for controlling the supply of motive fluid to said cylinder, fluid responsive means for operating the pilot valve to admit motive fluid to said cylinder, a second fluid responsive means for operating the pilot valve, and means for actuating the pilot valve in response to the combined action of the two fluid responsive means and also in response to the movement of the piston, including a main lever operatively connected to said first fluid responsive means, a bell crank pivotally mounted upon the main lever and having one arm connected to the pilot valve, a transmitting lever having one end connected to a second arm of the bell crank, an operating connection between the second fluid responsive means and an intermediate portion of the transmitting lever, and a lever actuated by the movement of the piston and connected 105 to the opposite end of the transmitting lever to impart a counteracting movement to the pilot valve.

3. The combination of a cylinder, a piston 115 therein, a pilot valve for controlling the supply of motive fluid to the cylinder, pressure actuated means for operating the pilot valve, a second and independent pressure actuated means for operating the pilot valve, and means for actuating the pilot valve in response to the combined action of the two pressure actuated means and also in response to the movement of the piston, including a main lever operatively connected to the first pressure actuated means, a bell 120 crank mounted upon the main lever for movement bodily by the latter and having one arm connected to the pilot valve, a transmitting lever connected to a second arm of the bell crank, an operating connection be- 125

- tween the second pressure actuated means and a different portion of the transmitting lever, a lever mounted to be rocked laterally by the travel of said piston, and a connection between said last mentioned lever and a third portion of the transmitting lever to impart a counteracting movement to the pilot valve upon movement of the piston.
4. The combination of a cylinder, a piston therein, a frame mounted for movement by the piston, a pilot valve for controlling the supply of motive fluid to the cylinder, pressure actuated means for operating the pilot valve, a second and independent pressure actuated means for operating the pilot valve, and means for actuating the pilot valve in response to the combined action of the two pressure actuated means and also in response to the movement of the piston, including a main lever operatively connected to the first pressure actuated means, a bell crank mounted upon the main lever and having one arm connected to the pilot valve, a lever mounted to be rocked laterally by the travel of said piston, a transmitting lever having an end operatively connected to the last
- mentioned lever and a portion spaced from said end connected to a second arm of said bell crank, and a connection between a third portion of the transmitting lever and said second pressure actuated means.
5. The combination of a cylinder, a piston therein, a pilot valve for controlling the supply of motive fluid to said cylinder, independently operable devices, a main lever, a bell-crank pivotally mounted on said main lever and connected to said pilot valve, means to rock said main lever from one of said devices and move the bell-crank to shift the pilot valve, means to rock said bell-crank from the other device and move the bell-crank to shift the pilot valve, a rock arm, a shoe pivotally connected to said rock arm, an inclined member slidably mounted in said shoe and adapted to be moved therein by said piston to rock said rock arm, and means to impart movement from said rock arm to said bell-crank to reverse the pilot valve.

In testimony whereof, I have signed my name to this specification.

FRANCIS H. BROWN.
